TELEVISION SYSTEM

Alda V. Bedford, Collingswood, N. J., assignor to
 Radio Corporation of America, a corporation of
 Delaware

Application November 28, 1936, Serial No. 113,130

1 Claim. (Cl. 178—6.8)

My invention relates to television systems and particularly to systems of the type employing cathode ray transmitter tubes and cathode ray receiver tubes.

In television systems of this type, the cathode ray in the transmitter tube scans a photoelectric screen to produce picture signals while the cathode ray in the receiver tube scans a fluorescent screen to produce a picture thereon corresponding to said signals. Scanning at both transmitter and receiver is accomplished by deflecting the cathode ray horizontally by means of a saw-tooth wave recurring at a comparatively high frequency and by simultaneously deflecting it vertically by means of a saw-tooth wave recurring at a comparatively low frequency. Synchronization of scanning at the transmitter and at the receiver is maintained by transmitting a synchronizing impulse at the end of each scanning line and at the end of each picture frame.

It is the usual practice to prevent the production of a return line trace on the fluorescent screen of the cathode ray receiver tube by cutting-off or blocking the cathode ray during the return line period, both for horizontal and vertical deflection. It has also been found advisable to cut off the cathode ray in the transmitter tube during the return line period for both horizontal and vertical deflection. This prevents the cathode ray from partially discharging the photoelectric screen during the return line period. I have found that the above mentioned blocking of the transmitter tube cathode ray creates an electrical disturbance which it is difficult to eliminate entirely at the transmitter.

It is, accordingly, one object of my invention to provide a method of and means for eliminating at a television receiver substantially all disturbing effects due to blocking of the cathode ray in the transmitter tube.

A further object of my invention is to provide a method of and means for insuring that the transmitter tube cathode ray is blocked for the entire duration of a return line period.

More broadly, an object of my invention is to provide a method of and means for avoiding undesirable effects at a cathode ray receiver tube due to the return deflection of the cathode ray in the transmitter tube.

In practicing my invention I apply a rectangular voltage impulse to the control grid of the cathode ray transmitter tube to block the ray during the return line period and I make this impulse of greater duration than the driving or synchronizing impulse which is supplied to the transmitter tube deflecting circuit. Also, I transmit to the receiver a rectangular voltage impulse which blocks the ray of the cathode ray receiver tube during the return line period, and I make

this impulse of greater duration than the cathode ray blocking impulse at the transmitter.

My invention will be better understood from the following description taken in connection with the accompanying drawings in which—

Figs. 1 and 2 are block diagrams of a television transmitter and of a television receiver, respectively, in a system embodying my invention.

Fig. 3 is a group of curves which are referred to in explaining my invention.

Figs. 4a to 4e are curves which are referred to in explaining my invention.

Fig. 5 is a circuit diagram of a portion of the transmitter shown in Fig. 1, and

Fig. 6 is a group of curves that are referred to in explaining the operation of the circuit shown in Fig. 5.

Referring to Fig. 1, there is illustrated a television transmitter of the general type described and claimed in my copending application, Serial No. 728,147, filed May 29, 1934, and assigned to the Radio Corporation of America. The impulse generator indicated at 1 may be of the type employing rotating discs as described in the said copending application, but preferably it is of the type described and claimed in Patent No. 2,132,655, issued October 11, 1938, in the name of John P. Smith and assigned to the Radio Corporation of America.

As described in the said Smith application, the generator 1 may be designed to supply synchronizing or "driving" impulses through conductors 2 and 3 to the horizontal and vertical deflecting circuits 4 and 6, respectively, of the cathode ray transmitter tube 7. Also, as shown in the Smith application, the generator 1 may supply blanking impulses through a conductor 8 and receiver synchronizing impulses through a conductor 9.

The transmitter tube 7 is of a well known type comprising an evacuated envelope having therein an indirectly heated cathode 11, a control grid 12, a first anode 13, a second anode 14 and a photoelectric screen or mosaic 16. The screen 16 may consist of a sheet of mica or other insulating material 17 having a metallic surface 18 on the back side and having a mosaic of microscopic globules 19 on the front side. The globules are light-sensitive elements such as silver globules coated with caesium and are insulated from each other as well as from the surface or "back plate" 18.

The electrodes of the tube 7 are maintained at suitable potentials by means of connections to the voltage divider 21 of a power supply unit (not shown), the control grid 12 being connected to a negative point on the voltage divider through a resistor 22.

The metal surface or "back plate" 18 is connected through an output resistor 23 to ground. When the image of a scene to be transmitted is

projected upon the mosaic 19 and the mosaic is then scanned, picture signals appear across the resistor 23.

The picture signals are supplied through a picture amplifier 24 to a radio transmitter 26 and radiated to a suitable television receiver. As will be described more fully, and as is described in my above mentioned application, the picture signals are properly combined with blanking and synchronizing impulses before they are transmitted, the blanking signals being supplied from the conductor 8 through an amplifier 27 and a conductor 28 to one stage of the amplifier 24, and the synchronizing signals being supplied 10 from the conductor 9 through the amplifier 29 and the conductor 31 to a succeeding stage in amplifier 24.

In order to block the cathode ray of the transmitter tube 7 during the return line period, the 20 impulses supplied over conductors 2 and 3 are added through resistors 32, 33 and 34 and impressed upon the control grid 12 through an amplifier 36.

In accordance with one feature of my invention, the blanking impulses which are impressed 25 upon control grid 12 are wider, that is, of greater duration, than the driving impulses supplied to the transmitter tube deflecting circuits 4 and 6. For convenience, and in order to make the block 1 30 correspond exactly to the disclosure of the above mentioned Smith application, I have shown a circuit wherein the impulses supplied over conductors 2 and 3 are employed without any change in width for blanking and are narrowed by shaping networks 37 and 38, respectively, before being impressed upon the deflecting circuits.

The shaping networks 37 and 38 may be designed in several ways, one satisfactory design being shown in Fig. 5, which is a circuit diagram 40 of the network 37. Referring to Fig. 5, this particular network includes four resistance coupled vacuum tubes 39, 41, 42 and 43. The rectangular impulses indicated at 40 which are supplied over conductor 2 (Fig. 1) are impressed 45 upon the input circuit of the vacuum tube 39 through a coupling condenser 44 and a resistor 46 of comparatively high resistance. The input circuit of the tube 39 includes a resistor 47 of comparatively high resistance connected between the 50 grid and the cathode of the tube 39, this resistor being shunted by a condenser 48 of comparatively large capacity. The circuit including the resistance 47 and condenser 48, which may be referred to as an integrating circuit, causes the 55 rectangular impulse 40 to acquire the shape indicated at 49. The reshaped impulse 49 is then clipped by the tube at the level indicated by the dotted line 51 to produce in the output circuit of the tube 39 an impulse of the shape indicated 60 at 52. It will be understood that the grid of the tube 39, and the grids of the other tubes in the circuit which function to clip the impulses, is maintained at the desired negative bias by means of the well known grid leak biasing action.

The tube 41 is employed merely for the purpose of reversing the polarity of the impulse to produce the impulse indicated at 53. This impulse is then impressed upon what may be described as a differentiating circuit comprising a 70 coupling condenser 54 of very small capacity and a grid resistor 56 of comparatively low resistance. The resulting impulse appearing across the input electrodes of the tube 42 has a wave shape indicated at 57. The reason that the impulse has been reshaped in this way is that it has been

caused to lose its low frequency components. The impulse 57 is then clipped by the tube 42 at the level indicated by the dotted line 58 to produce at the input circuit of the tube 43 an impulse having the shape indicated at 59. The tube 43 5 clips the impulse 59 at the level indicated by the dotted line 61 to produce the desired rectangular narrowed impulse indicated at 62.

The action of the circuit shown in Fig. 5 may be better understood by referring to Fig. 6, where 10 impulses corresponding to those shown in Fig. 5 are indicated by the same reference numerals. It will be seen that the incoming rectangular impulse 40 is caused by the integrating circuit to have a sloping "front" side of increasing amplitude for the duration of the original impulse and a sloping "back" side of decreasing amplitude beginning at the termination of the original rectangular impulse. By clipping this resulting impulse 51 at a certain level, an impulse of the 20 desired width may finally be produced. After the impulse 51 is clipped, it has the shape indicated at 53. By passing impulse 53 through a differentiating circuit, the gradually sloping "front" side of the impulse causes a narrow substantially rectangular portion to be produced in the resulting impulse 57. It will be noted that the flat clipped portion of the impulse 53 causes a corresponding flat portion to appear in the impulse 57, since the amplitude of the signal is not 30 changing in this region. It is apparent that, by clipping the impulse 57 as indicated, the desired narrow impulse 62 is obtained.

Figs. 4a to 4e show the relative widths of the horizontal driving and blanking impulses. The 35 impulses 62 shown in Fig. 4a are the impulses which appear in the output circuit of the impulse shaper 37, these impulses occurring in the specific transmitter being described at the rate of 10,290 per second. Each of these impulses is the same 40 as the impulse 62 shown in Fig. 5, the impulse in Fig. 5 being shown with vertical sides for the purpose of simplifying the drawing. It will be understood that it is practically impossible to obtain a rectangular impulse having sides which 45 do not slope at all, or to transmit it through the circuits if it is obtained.

Fig. 4b shows the saw-tooth current wave which passes through the horizontal deflecting coils of the transmitter tube 7 as a result of the horizontal driving impulses being impressed upon the 50 deflecting circuit 4. It will be noted that, after the termination of the driving impulse 62, considerable time is required for the cathode ray of the tube 7 to complete its return and start upon 55 the linear portion, that is the useful portion, of its scanning cycle. This is due to the inductance of the deflecting yoke and to the time required to charge distributed capacities of the circuit and also to the delay in transmission through the 60 cable which connects the deflecting circuits to the deflecting coils. Hence, the duration of the transmitter tube driving or synchronizing impulses 62 should be shorter than the transmitter tube blanking impulses in order that the blanking 65 may include all of the return period of the transmitter tube.

The transmitter tube blanking impulses, which may be the impulses 40 unchanged in width, are shown in Fig. 4c. It will be seen that 70 they have a width or duration enough greater than that of the driving impulses to block the cathode ray completely during the return line period. Actually, the transmitter tube blanking impulse, as it appears at the control grid 12 of 75

the transmitter tube, will have the shape shown in Fig. 4d, this shape being due largely to distributed capacity in the circuit.

The horizontal blanking impulses 60 which are transmitted to the television receiver for blanking out the receiver cathode ray during the return line period are shown in Fig. 4e. These impulses have a greater width or duration than the blanking impulses shown in Fig. 4d, whereby any disturbances produced at the transmitter as the result of blocking the cathode ray are prevented from appearing on the fluorescent screen of the receiver tube.

It may be noted that if the blanking impulses at the transmitter and receiver are of the same width, the disturbance produced by blocking the transmitter ray may not be included (in time) by the receiver blanking impulse due to the slight delay in the transmission of the transmitter tube blanking impulse through a cable to the cathode ray tube and to the inadequate steepness of the wave fronts of the impulses actually reaching the respective control grids of the cathode ray transmitter and receiver tubes.

The above mentioned considerations apply to the widths of the vertical synchronizing and blanking impulses, as well as to the widths of the horizontal impulses. This will be seen by referring to Fig. 3, wherein the nature of the synchronizing and blanking impulses is more completely illustrated. One of the vertical synchronizing or driving impulses for the transmitter tube 7 is indicated at 63. This impulse is supplied from the conductor 3 (Fig. 1) through the network 38 to the vertical deflecting circuit 6. The vertical synchronizing impulses occur at the rate of 60 per second in the specific transmitter being described. The horizontal synchronizing or driving impulses for the transmitter tube indicated at 62 are the same as those shown in Fig. 4a, the impulses being shown with straight sides in order to simplify the drawings.

One of the vertical blanking impulses which are supplied through the amplifier 36 to the grid 12 is indicated at 64. These impulses are wider than the vertical driving impulses 63, as will be seen from an inspection of the curves. In this figure the difference in width of the horizontal synchronizing impulses 62 and the horizontal blanking impulses 60 is not shown.

The combined horizontal and vertical blanking impulses which are transmitted over the conductor 8 to the picture amplifier 24 for transmission to the receiver are shown under the legend "Receiver blanking." It will be seen that the vertical blanking impulse 66 for the cathode ray receiver tube is of substantially greater duration than the transmitter tube blanking impulse 64. The complete signal which modulates the carrier of the radio transmitter 26 is indicated at the bottom of the figure, the horizontal and vertical blanking impulses being indicated at 60 and 66, respectively, and the horizontal synchronizing and the "slotted" vertical synchronizing impulses which are set on top of the blanking impulses being indicated at 67 and 68, respectively. The picture signal appears between the blanking impulses 60, as indicated at 69, "black" in the picture being represented by the top of the blanking impulse or "pedestal," indicated at 71.

While I have shown the vertical driving or synchronizing impulses and the vertical blanking impulses as beginning at the same time, it should be understood that it may be desirable to

have the transmitter tube blanking signals begin slightly ahead of the transmitter tube driving impulses and it may also be desirable to have the receiver tube blanking impulses begin slightly ahead of the transmitter tube blanking impulses as is indicated in Figs. 4a to 4e for the horizontal driving and blanking impulses.

The several impulses may be made to start one ahead of the other by employing any suitable delay network, transmission line, or the like for delaying certain impulses. For example, delay networks 30 and 40 may be included in the horizontal and vertical deflecting channels for delaying the driving impulses a certain amount. A delay circuit or network may be included in the amplifier 36 for delaying the blanking impulses for the tube 7 a less amount while the blanking impulses for the receiver may be transmitted with substantially no delay.

The receiver shown in Fig. 2 may be of a well-known type including a cathode ray tube 72 having horizontal and vertical deflecting coils. The picture, blanking and synchronizing signals, shown by the bottom curve in Fig. 3, are impressed upon the control grid 73 of the cathode ray tube through a radio receiver 74 and picture amplifier 76. This same signal is supplied to a separating circuit 77 where substantially all of the picture signal is removed and the horizontal and vertical synchronizing impulses separated and supplied to their respective deflecting circuits 78 and 79. It will be understood that these deflecting circuits are of any suitable type for producing saw-tooth deflection of the cathode ray.

The cathode ray tube itself may be of conventional design including an evacuated member having therein an indirectly heated cathode 81, the control grid 73, a first anode 82, a second anode 83, and a fluorescent screen 84. In the specific tube illustrated, the cathode ray is electrostatically focused.

From the foregoing description, it will be seen that, by employing my invention, all disturbances produced at the transmitter by reason of the return deflection of the cathode ray are prevented from having any effect upon the fluorescent screen 84 of the receiver.

I claim as my invention:

In a television system of the type employing a cathode ray transmitter tube at the transmitter for producing picture signals and a cathode ray receiver tube at the receiver for reproducing the transmitted picture on a receiving screen, said tube at the transmitter being of the type including a screen comprising a mosaic of elements each capable of storing an electric charge, the method which comprises causing the cathode ray in said receiver tube to scan the receiving screen whereby it has a useful scanning period and a return line period, causing the cathode ray of said transmitter tube to scan said mosaic over an area substantially greater than the area of the mosaic covered by the picture to be reproduced and in synchronism with the scanning of said receiving screen and with its useful scanning period greater than and with its return line period less than the corresponding periods at said receiver, and blocking the cathode ray in said receiver tube for a period which includes the beginning and the end of the useful deflecting period of the cathode ray of said transmitter tube as well as the return line period of the cathode ray of said transmitter tube.

ALDA V. BEDFORD. 75
